UNITED STATES PATENT OFFICE.

WALTER A. SIMOND, OF FRANKLIN, NEW HAMPSHIRE, ASSIGNOR TO ACME KNITTING MACHINE & NEEDLE COMPANY, OF FRANKLIN, NEW HAMPSHIRE, A CORPORATION OF NEW HAMPSHIRE.

DIAL-HOLDING MECHANISM.

Application filed November 17, 1919. Serial No. 338,678.

To all whom it may concern:

Be it known that I, WALTER A. SIMOND, a citizen of the United States, residing at Franklin, in the county of Merrimack and 5 State of New Hampshire, have invented certain Improvements in Dial-Holding Mechanisms, of which the following description, in connection with the accompanying drawings, is a specification, like reference characters on the drawings indicating like parts in the several figures.

This invention relates to knitting machines of the dial type. It is necessary in circular knitting machines of this type to 15 provide some means for holding the dial stationary. The present invention aims to provide a superior mechanism for performing this function and especially to devise a mechanism of this character in which cam 20 operated slides usually employed for this purpose and which are liable to produce a rocking motion of the dial will not be required.

The nature of the invention will be readily understood from the following description when read in connection with the accompanying drawings, and the novel features will be particularly pointed out in the appended claims.

Referring now to the drawings,

Figure 1 is a vertical cross sectional view through the upper part of one form of knitting machine equipped with a mechanism embodying the present invention;

Fig. 2 is a perspective view of the dial holding mechanism shown in Fig. 1;

Fig. 3 is a plan view of a modified form of the invention; and

Fig. 4 is a vertical cross sectional view of the mechanism shown in Fig. 3.

The invention is herein illustrated as applied to a circular knitting machine of the type in which either plain or ribbed work may be knitted at will, although it is obvious that the invention is equally applicable to machines designed simply for ribbing. The drawings show the invention as applied to the machine disclosed in application Serial No. 293,113 filed April 28, 50 1919.

In the drawings, 2 designates the dial plate in which the horizontal needles are supported and guided, the needles being operated by a cam 3 secured to the lower end of a sleeve 4. The upper end of said

sleeve is clamped in the yoke 5 which is rigidly connected with the cam cylinder of the machine and consequently rotates with said cylinder, as will be evident to those skilled in this art. The dial 2 is pinned 60 to a shaft or post 6 which extends upwardly through a sleeve 4 and projects beyond the upper end of said sleeve. Keyed to the upper end of the shaft 6 is a spur gear 7 provided with a hub that extends 65 both above and below the faces of the gear, as clearly shown in Fig. 1. An internal gear 8 encircles the spur gear 7 and is fastened by screws 10 to the upper surface of a bracket 12 which is secured rigidly to 70 the machine frame. A circular aperture is formed in this bracket to snugly receive a disk 14 which is secured fast to the upper end of the yoke 5 by means of screws, one of which is shown at 15. A planetary gear 75 ing is carried by the disk 14 and positively connects the internal gear 8 with the spur gear 7, this gearing being of such a ratio that as the disk 14 revolves with the cam cylinder of the machine the planetary 80 gearing will hold the spur gear 7 stationary. This planetary gearing is best shown in Fig. 2 and comprises a spur gear 16 meshing with the internal gear 8, another spur gear 17 fast on the shaft 18 85 and meshing with the gear 16, and a pinion 19 also fast on said shaft 18 and meshing with the spur gear 7. A stub shaft 22 carried by the disk 14 supports the gear 16.

It will be clear that since this gearing 90 forms a positive connection between the stationary gear 8 and the spur gear 7, it is only necessary to select the proper gear ratio to enable this gearing to hold the spur gear 7 against rotative movement, and since this spur gear is secured fast to the dial 2 it is obvious that if the gear is held stationary the dial also must be held stationary. In order to permit an angular adjustment of the stationary annular gear 8 in its seat in the bracket 12, slots are provided in the gear through which the screws 10 extend, as clearly shown in Fig. 2.

For the purpose of guiding the thread or yarn to the thread ring, a thread tube 20 is secured in the disk 14 and extends therethrough so that it will rotate in unison with the needle operating cam. Since the planetary gearing is carried by the disk 14 there is no possibility of interference 110

between the thread tube and this gearing. A cover plate 21 cooperates with the bracket 12, disk 14, and the gear 7 and its hub to form a tight enclosure for the gears which protects them from the dust. If desired, this enclosure may be packed with grease. The thread tube 20 extends through this enclosure and cooperates with the shaft 18 to rotate the cover plate 21 with the disk 14.

A somewhat different form of the invention is illustrated in Figs. 3 and 4 in which the parts corresponding to those shown in Figs. 1 and 2 are designated by the same numerals as those used in the latter figures, the numerals, however, being primed. In this form of the invention the same general construction is employed but it includes some refinements in mechanical details. The bracket 12' is secured by a set screw 24 to a rod 25 that is supported in another bracket 26 mounted for vertical adjustment on a stationary rod 27, the connections between the parts 25, 26 and 27 being made by set screws 28 and 29, Fig. 3. This construction is of advantage since, whenever it is desired to disconnect the shaft 6' from the dial holding mechanism, as, for instance, when the rib dial is to be changed, it is merely necessary to loosen the set screw 29, whereupon the brackets 26 and 12' can be raised until the lower edge of the bracket 12' clears the upper end of the shaft 6'. The parts so elevated can then be swung out of the way of the remaining parts of the mechanism.

In this construction also a less expensive method of locating and holding the internal gear 8' is employed. A groove 36 having a downwardly inclined wall is cut in the peripheral edge of the gear, as clearly shown in Fig. 4, and set screws 30 are threaded through the bracket 12' and engage the inclined wall of this groove, the set screws thus operating to secure the gear 8' firmly in its seat and at the same time providing for the convenient adjustment of this gear.

The central gear 7' in this construction rests on a thrust washer 31 instead of resting directly on the top of the sleeve 4, as in the construction previously described. This arrangement has the advantage of permitting a vertical adjustment of the parts 3 and 4 without disturbing the shaft 6' or the gear 7'.

The form of the invention shown in Figs. 3 and 4 also differs from that above described in that the studs 32 and 33, respectively, on which the gears 16' and 17' rotate, are provided with shoulders, the shoulder on the stud 32 being indicated at 37, Fig. 4. These shoulders or enlargements bear on the bottoms of sockets formed in the upper surface of the disk 14' and the threaded shank of each stud projects

through the disk and has a nut, such as 34, Fig. 4, threaded thereon to secure it firmly to the disk. By locating these studs in slots of suitable shape, as indicated at 34 and 35, Fig. 3, provision is made for adjusting the gears to take up any back lash or lost motion that may develop as the gears become worn. In this connection it may also be stated that if any thrust develops later to disturb the position of the central gear, such thrust can be balanced by changing the position of the yarn tube and using one or two more sets of planetary gears in opposite positions.

It will now be evident that this invention provides a very simple mechanism for holding the dial against rotation and guiding the thread to the thread ring, that this mechanism can be very economically manufactured, and that it avoids the rocking of the dial which frequently is produced by the cam slide mechanisms for performing this function.

What is claimed as new is:

1. In a knitting machine having a needle dial and a cam for operating the needles mounted in said dial, a mechanism for holding the dial stationary while the cam revolves, comprising, in combination, an annular gear, means supporting said gear in a fixed position, a second gear of smaller pitch circle than said annular gear, said second gear being rigidly connected with said dial and positioned substantially within said annular gear, and planetary gearing connected with said cam to rotate therewith and positively connecting said gears, said planetary gearing being of a ratio to maintain said second gear stationary.

2. In a knitting machine having a needle dial and a cam for operating the needles mounted in said dial, a mechanism for holding the dial stationary while the cam revolves, comprising, in combination, a dial shaft to which the dial is secured, a yoke rotating with said cam, a disk connected with said yoke to rotate therewith, a stationary bracket having an aperture therein to receive said disk and supporting the edge of the disk, an annular gear secured to said bracket, a second gear secured to said shaft, and planetary gearing connected with said cam to rotate therewith and positively connecting said annular gear with said second gear, said planetary gearing being of a ratio to maintain said second gear stationary.

3. In a knitting machine having a needle dial a cam for operating the needles supported in said dial, a mechanism for holding the dial stationary while the cam revolves, comprising, in combination, a dial shaft to which the dial is secured, a yoke rotating with said cam, a disk secured to said yoke, said shaft projecting through said disk, a spur gear secured to said shaft 125

above the yoke, a stationary bracket having an aperture therein to receive said disk, an internal gear secured to said bracket, planetary gearing supported by and rotating with said disk and positively connecting said internal gear with said spur gear, said gearing being of a ratio to maintain said spur gear stationary while said disk rotates, and a thread tube mounted in said 10 disk.

4. In a knitting machine having a needle dial and a cam for operating the needles mounted in said dial, a mechanism for holding the dial stationary while the cam revolves, comprising, in combination, an annular gear, means supporting said gear in a fixed position, a second gear rigidly connected with said dial and positioned closely adjacent to said annular gear, planetary gearing connected with said cam to rotate therewith and positively connecting said gears, said planetary gearing being of a ratio to maintain said second gear stationary, parts cooperating to enclose said gears, and a thread tube extending through said enclosure and mounted to rotate with said planetary gearing.

5. In a knitting machine having a needle dial and a cam for operating the needles mounted in said dial, a mechanism for holding the dial stationary while the cam revolves, comprising, in combination, a stationary annular gear, a second gear rigidly connected with said dial, said second gear being of smaller pitch circle than said annular gear and located substantially within the latter gear, means supporting said annular gear for adjustment substantially axially thereof into and out of cooperative relationship to said second gear, planetary gearing positively connecting said gears, said planetary gearing being of a ratio to maintain said second gear stationary, and a support

for said planetary gearing connected with said cam to rotate therewith. 45

6. In a knitting machine having a needle dial and a cam for operating the needles supported in said dial, a mechanism for holding the dial stationary while the cam revolves, comprising, in combination, a spur gear rigidly connected with said dial, an internal gear mounted closely adjacent to said spur gear, a disk mounted above said dial closely adjacent to said internal gear and connected with said cam to rotate therewith, means for holding said internal gear stationary and for supporting said disk against lateral movement, and planetary gearing supported by said disk and positively connecting said spur gear and said internal gear, said gearing being of a ratio to maintain said spur gear stationary. 50 55 60 65

7. In a knitting machine having a needle dial and a cam for operating the needles supported in said dial, a mechanism for holding the dial stationary while the cam revolves, comprising, in combination, a dial shaft to which the dial is secured, a yoke rotating with said cam, a disk secured to said yoke, said shaft projecting through 70 said disk, a spur gear secured to said shaft above the yoke, a stationary bracket having an aperture therein to receive said disk, an internal gear secured to said bracket, planetary gearing supported by and rotating with 75 said disk and positively connecting said internal gear with said spur gear, said gearing being of a ratio to maintain said spur gear stationary while said disk rotates, and means supporting said planetary gearing on 80 said disk constructed and arranged to enable said gearing to be adjusted to take up lost motion as the gears become worn.

In testimony whereof I have signed my name to this specification.

WALTER A. SIMOND.
